INVENTOR
William C. Althen

BY C. C. Shepherd,

ATTORNEY

UNITED STATES PATENT OFFICE.

WILLIAM C. ALTHEN, OF COLUMBUS, OHIO.

NUT-LOCK.

SPECIFICATION forming part of Letters Patent No. 578,591, dated March 9, 1897.

Application filed October 5, 1896. Serial No. 607,871. (No model.)

To all whom it may concern:

Be it known that I, WILLIAM C. ALTHEN, a citizen of the United States, residing at Columbus, in the county of Franklin and State of Ohio, have invented a certain new and useful Improvement in Nut-Locks, of which the following is a specification.

My invention relates to the improvement of nut-locks, and has particular relation to the construction of nut-locks for use on wagon-spindles and other similar places.

The objects of my invention are to provide an improved nut-lock of this class of such construction and arrangement as to prevent a nut from working off the spindle and to produce said nut-lock in a simple and inexpensive form. These objects I accomplish in the manner illustrated in the accompanying drawings, in which—

20 Figure 1 is a longitudinal section of a portion of a wagon-spindle having my improved nut-lock in connection therewith. Fig. 2 is an end view of the spindle, showing the nut-lock thereon. Fig. 3 is a side elevation of 25 one of the parts of my improved locking device, and Fig. 4 is a view taken from the opposite side from that shown in Fig. 3.

Similar letters refer to similar parts throughout the several views.

30 *a* represents a vehicle-spindle, the threaded outer end portion of which is adapted to receive a nut *a'* in the usual manner.

b represents one of the parts of my improved lock, which is in the form of a disk and which is provided with a continuous peripheral groove *b'*. The forward face and upper side of the disk *b* has formed therein a short way or channel *c*, which leads into the groove *b'*, while a similar way or channel

40 *d* is formed in the lower side of the disk *b*, and also communicates with the groove *b'*. Adjacent to the opening *d* the groove or channel *b* is provided in its inner wall with a recess *e*. Adjacent to the opening *c* the inner

45 wall of the groove *b* is provided with a shoulder *e'*. As indicated in the drawings, the inner line or wall of the groove *b'* extends to the recess *e* in a slightly-inclined direction.

Through the central opening of the disk *b* 50 is adapted to pass the usual axle lag-screw *f*, the head of the latter bearing against the outer face of the disk *b* and retaining said disk against the end of the axle-spindle.

g represents a locking-ring, the inner sur-

face of which is provided, as indicated more 55 clearly in Fig. 2 of the drawings, with oppositely-located inwardly-projecting lugs *g'* *g''*. This ring *g* is, as indicated in the drawings, adapted to embrace the disk *b*, the lugs *g'* and *g''* gaining entrance to the groove *b'* 60 through the medium of the ways *c* and *d*. The lugs having thus been made to enter the disk-groove the locking-ring is turned downward, the lugs *g'* and *g''* traveling in the groove *b'* until the lug *g* drops into the recess *e* on 65 the under side of the disk and the lug *g'* is against the shoulder *e'* of the upper side of the disk.

As indicated in the drawings, I preferably provide the ring *g* on one side, which becomes 70 the lower side when said ring is in the locked position, with a stem *h*, which serves partly as a weight to retain the ring in a locked position and indicates to the eye whether or not said ring is in a locked position. On the inner face of the ring *g* and in the upper portion thereof I have provided a forwardly-projecting boss or lug *k*, which is adapted to come into contact with the outer face of the nut *a'* in case the latter is screwed inward 80 past the outer end of the spindle.

From the construction and operation which I have described it is obvious that a simple, effective, and inexpensive nut-lock is provided which may be employed in connection 85 with any of the ordinary constructions of wagons. It is also evident that by the use of my improved locking device any tendency of the nut toward working off the spindle is obviated and that said nut must retain its 90 place on the spindle until the ring *g* is inverted and detached from the disk *b*.

Having now fully described my invention, what I claim, and desire to secure by Letters Patent, is—

95 In a nut-lock the combination with a spindle, a nut thereon and a disk secured against the end of said spindle, a peripheral groove in said disk and oppositely-located ways leading to said groove, of a ring *g* having oppositely-located forwardly-projecting lugs, the latter being adapted to enter said disk-groove through the medium of said ways, substantially as and for the purpose specified.

WILLIAM C. ALTHEN.

In presence of—

C. C. SHEPHERD,
E. W. BRINKER.
